UNITED STATES PATENT OFFICE

150,528

DESIGN FOR A COMBINED CIGARETTE CONTAINER AND LAMP

Carl J. Zahn, Detroit, Mich.

Application November 14, 1946, Serial No. 134,792

Term of patent 3½ years

(Cl. D85—2)

To all whom it may concern:

Be it known that I, Carl J. Zahn, a citizen of the United States, residing in Detroit, county of Wayne, in the State of Michigan, have invented a new, original, and ornamental Design for a Combined Cigarette Container and Lamp, of which the following is a specification, reference being made to the accompanying drawing, forming part thereof.

The drawing shows a perspective view of a combined cigarette container and lamp, embodying my design.

The essential features of my design reside in the portion shown in solid lines.

I claim:

The ornamental design for a combined cigarette container and lamp, as shown and described.

CARL J. ZAHN.
